UNITED STATES PATENT OFFICE.

CHARLES T. WAGNER, OF COLLEGE POINT, NEW YORK.

DESIGN FOR QUILTING.

SPECIFICATION forming part of Design No. 18,401, dated June 19, 1888.

Application filed January 27, 1888. Serial No. 262,182. Term of patent 7 years.

To all whom it may concern:

Be it known that I, CHARLES T. WAGNER, of College Point, Queens county, State of New York, have originated and produced a new 5 Design for Quilting, of which the following is a specification.

My design relates to quiltings which are manufactured for linings for skirts, for garments, and for bed-coverings.

10 The design consists in a number of rows of circles and intermediate rows of bracket-like figures, alternate rows of bracket-like figures being so arranged that the bracket-like figures will extend in reverse directions from those of 15 the adjacent rows, and the different rows of circles being staggered.

The accompanying drawing is a view of a piece of quilting embellished with my design.

It consists, essentially, of rows of circles a' a'' , 20 which are staggered, or, in other words, so ar-

ranged that the circles of the rows a'' are opposite the spaces between the circles of the rows a' . Between the rows of circles are lines shown as bracket-like figures b' b'' . The bracket-like figures of the rows b' extend in a different direction from the bracket-like figures of the rows b'' . The bracket-like figures are shown as extending to the circles a' a'' , and as touching these circles at about the middle thereof.

What I claim as new, and desire to secure by Letters Patent, is—

The design for quilting, composed of rows of staggered circles and intermediate rows of connecting lines, substantially as shown and 35 described.

CHAS. T. WAGNER.
